UNITED STATES PATENT OFFICE

STEPHEN N. SMITH, OF PROVIDENCE, RHODE ISLAND.

DESIGN FOR A LACING-HOOK.

SPECIFICATION forming part of Design No. 12,141, dated January 18, 1881.

Application filed September 28, 1880. Term of patent 14 years.

To all whom it may concern:

Be it known that I, STEPHEN N. SMITH, of Providence, in the county of Providence and State of Rhode Island, have invented a Design for Lacing-Hooks, of which the following is a specification.

Heretofore lacing-hooks have been constructed in various forms, presenting to the eye various features or characteristics.

My design embraces a combination of features or characteristics never before combined in a hook, in consequence of which my hook presents, even to the eye of the unskilled person, a distinctive appearance by which it can be readily distinguished from all others which have preceded it.

My design embraces a flat top or face, a , of substantially circular form, a neck or portion, b , curving downward and inward from one edge of the face a , and a hollow rounded neck or body, c , joined to the lower end of the portion b , as represented. The inner side of the neck portion b is convex in cross-section and the outer surface concave, as shown. The top or face a is, as before stated, flat on its upper or outer surface, and has square or substantially square edges. This flat face, which is instantly and clearly distinguishable from a rounded or convex face, is a leading feature of my design. 25

What I claim is—

The design embracing the flat circular face or top a , the concavo-convex neck b , and the round body c , having the open center. 30
